Gerald L. Schwarz, Cleveland, Ohio, assignor to
Air Controls, Inc., Cleveland, Ohio, a corpora-
tion of Ohio

Application July 24, 1936, Serial No. 64,025

Term of patent 7 years

To all whom it may concern:

Be it known that I, Gerald L. Schwarz, a citizen of the United States, residing at 11802 Thornwood Avenue, Cleveland, in the county of Cuyahoga and State of Ohio, have invented a new, original, and ornamental Design for a Ventilator Casing or Similar Article, of which the following is a specification, reference being had to the accompanying drawing, forming part hereof.

Fig. 1 is a front perspective view of a ventilator casing showing my new design.

Fig. 2 is an elevational view of the rear side of the same.

Fig. 3 is a side elevational view looking from the left of Fig. 1.

Fig. 4 is a top elevational view.

I claim:

The ornamental design for a ventilator casing or similar article, as shown and described.

GERALD L. SCHWARZ.
